US00D982759S

(12) **United States Design Patent** (10) Patent No.: **US D982,759 S**
 Qian et al. (45) Date of Patent: ** Apr. 4, 2023

- (54) **MULTI-PARAMETER DETECTOR FOR MEDICAL USE**
- (71) Applicant: **BEIJING CHOICE ELECTRONIC TECHNOLOGY CO., LTD.**, Beijing (CN)
- (72) Inventors: **Xiaolun Qian**, Beijing (CN); **Chuanlong Ma**, Beijing (CN); **Zesheng Xi**, Beijing (CN)
- (**) Term: **15 Years**
- (21) Appl. No.: **35/515,143**
- (22) Filed: **Aug. 9, 2022**
- (80) **Hague Agreement Data**
- Int. Filing Date: **Aug. 9, 2022**
 Int. Reg. No.: **DM/223169**
 Int. Reg. Date: **Aug. 9, 2022**
 Int. Reg. Pub. Date: **Sep. 16, 2022**
- (51) **LOC (14) Cl.** **24-02**
 (52) **U.S. Cl.**
 USPC **D24/167**
 CPC ..... **A61B 5/7203 (2013.01)**
- (58) **Field of Classification Search**
 USPC ..... D24/107, 167, 186, 187, 158, 216, 218, D24/224, 225; D10/70, 75, 97, 98, 46; D14/344, 138 C, 138 R

Primary Examiner — Richard E Chilcot

(57) **CLAIM**

The ornamental design for multi-parameter detector for medical use, as shown and described.

DESCRIPTION

1. Multi-parameter detector for medical use
- 1.1 Front
- 1.2 Back
- 1.3 Left
- 1.4 Right
- 1.5 Top
- 1.6 Bottom
- 1.7 Perspective

1 Claim, 7 Drawing Sheets
